UNITED STATES PATENT OFFICE.

WILLIAM A. STOETZER, OF WHEELING, WEST VIRGINIA.

MATERIAL FOR BINDING PLASTER TO CONCRETE SURFACES.

1,152,860.

Specification of Letters Patent.

Patented Sept. 7, 1915.

Application filed December 31, 1914. Serial No. 879,830.

To all whom it may concern:

Be it known that I, WILLIAM A. STOETZER, a citizen of the United States of America, and a resident of Wheeling, county of Ohio, and State of West Virginia, have invented certain new and useful Improvements in Material for Binding Plaster to Concrete Surfaces, of which the following is a specification.

- 10 This invention relates broadly to means for causing plaster to adhere to concrete surfaces, and more specifically to a material for binding a plaster coating to such surfaces.
- 15 Hitherto much difficulty has been encountered in so applying plaster coatings to concrete surfaces that they will closely adhere, due to the fact that such surfaces are necessarily more or less smooth and, consequently, no satisfactory means is afforded for binding the plaster thereto or for causing the plaster to firmly unite or bond therewith.

It is the object of the present invention, therefore, to provide in a commercially available and applicable form a binder, or binding material, by means of which a close bond between the concrete surface and a plaster coating may be obtained; or, in other words, to provide means whereby a plaster coating may be firmly bound to a concrete surface.

In describing the invention in detail, reference is herein had to the accompanying drawings, forming a part of this specification, in which—

Figure 1 is an edge view of the invention, showing the same attached to the inner face of a form for concrete and illustrating the manner of its application to a concrete surface which is to be plastered; Fig. 2 is a similar view showing the form removed, and illustrating a portion of the paper backing of my binder removed preparatory to applying a plaster coating; Fig. 3 is a sectional view showing a plaster coating applied, and illustrating the use of the binder; and Fig. 4 is an inner face view of a fragmentary portion of the article which constitutes my invention.

The invention comprises, essentially, a flexible backing 1, preferably of paper, to one face of which is applied a loosely tangled or matted mass of a suitable fibrous material 2, as animal hair, wood fiber, or cork fragments, said material being caused

to adhere lightly to the paper by a suitable adhesive substance.

In practice, the paper backing 1 is applied to the form in which the concrete is to be poured, being lightly attached to the inner face of that side 3 of said form which, when the concrete wall is formed, faces the surface to be plastered, as shown in Fig. 1. In this position, the loose portions of the fiber or other material 2 carried by the paper 1 project into the mold space and become embedded in the cement 4 when the latter is poured, as shown in Figs. 1, 2 and 3. When the form is removed, the fibers and paper backing, adhering to the surface of the concrete, strip from said form. Then, to prepare the concrete surface for the reception of a plaster coating, the paper backing is stripped off, leaving the loose ends or other portions of the fibers 2 projecting outward from said surface, as shown in Fig. 2. When the plaster coating 5 is applied, said projecting portions of the fibers receive and become embedded in said coating, as shown in Fig. 3. Thus, the fibers serve to firmly bind said coating to the concrete surface.

It will be understood that the coating of fibers carried by the paper backing may be as heavy or as light as desired. Experimentation has shown, however, that a very thin or light fiber coating will suffice.

As is obvious, the paper backing constitutes the means by which the fibers are maintained in properly distributed position during the formative period of the concrete; further, such backing is required to constitute an article having a form adapted for handling in a commercial way. The article is adapted to be put up and marketed either in strips or squares of a convenient size, or in rolls, preferably the latter.

What is claimed is—

1. As an article of manufacture, a backing of thin material having a covering of fibrous material lightly adhering to one face thereof.

2. As an article of manufacture, a paper backing having disposed in lightly adhering relation to one face thereof a loosely tangled mass of fibrous material.

3. A binder of the character described, comprising a flexible paper backing, and a mass of scattered thread-like fibers disposed in lightly adhering relation to one face of said backing.

4. A binder by means of which a plaster coating may be closely bonded to a concrete surface, said binder comprising a flexible backing, and a mass of scattered fibers disposed in lightly adhering relation to one face of said backing, the free ends of said fibers being adapted to become embedded in the concrete, and said backing being

adapted to be stripped from said fibers before the application of said coating.

In testimony whereof, I affix my signature in presence of two subscribing witnesses.

WILLIAM A. STOETZER.
